Primary Examiner — Catherine R Oliver-Garcia(74) *Attorney, Agent, or Firm* — Boudwin Intellectual Property; Daniel Boudwin(57) **CLAIM**

The ornamental design for a self-defender, as shown and described.

DESCRIPTION

FIG. 1 shows a perspective view of a self-defender. FIG. 2 shows a left side view of the self-defender. FIG. 3 shows a right side view of the self-defender. FIG. 4 shows a top plan view of the self-defender. FIG. 5 shows a bottom plan view of the self-defender. FIG. 6 shows a front view of the self-defender; and, FIG. 7 shows a rear of the self-defender. The shade lines in the Figures show contour and not surface ornamentation.
